UNITED STATES PATENT OFFICE.

OSCAR ANDREW ELLIS, OF SAN FRANCISCO, CALIFORNIA.

DRY-CRUSHING MILL.

Application filed May 31, 1918, Serial No. 237,462. Renewed July 14, 1923.

To all whom it may concern:

Be it known that I, OSCAR ANDREW ELLIS, a citizen of the United States, residing at San Francisco, in the county of San Francisco and State of California, have invented certain new and useful Improvements in Dry-Crushing Mills, of which the following is a specification.

My invention relates to crushing mills, and more particularly to mills of this character adapted to do dry grinding.

The invention will be illustrated and described in connection with a crushing mill of the ball type, such as covered by my co-pending application Serial No. 195,628, although in its broader aspects, it is by no means limited to this type.

As is well known, ball mills are usually operated by the wet method, that is to say, water is used to flush the grinding trough or runway and thus form the pulverized material into a kind of sludge which can then be run off through pipes. Many materials, however, such as magnesite, lime, cement, etc., must, of necessity, be handled dry. It is therefore the main object of the present invention to provide improved means for removing the dry pulverized material from such a mill as fast as it leaves the grinding balls and to convey it to the desired point.

Another object of the invention is to provide, in connection with a mill having a freely movable saddle of the type shown in my above mentioned application, suitable means for preventing excessive lateral displacement of the saddle due to the stress of the driving belt.

In order that the invention may be readily understood, reference is had to the accompanying drawings, forming part of this specification and in which,

Fig. 1 is a side elevation of a ball mill embodying my invention, parts being broken away and parts being shown in section;

Fig. 2 is a plan view thereof, parts being broken away;

Fig. 3 is a vertical section on the line 3—3 of Fig. 2, looking in the direction of the arrow; and,

Fig. 4 is a detailed face view, on an enlarged scale, of a cleaning brush hereinafter described.

Referring to the drawings in detail, the mill is erected on a suitable foundation 1, of concrete or the like. Set into this foundation is a vertical wall 2, which may conven-

iently be formed of sheet metal. Inside of this and disposed somewhat above the same is a second, substantially circular, wall 3, which encloses the grinding chamber and 60 balls and in which the usual screens are set.

4 designates the saddle which rests on a series of balls 14, adapted to roll in the annular trough or runway 13, supported on the concrete base 1.

On the upper face of the saddle 4 is an annular flange 4^a, and to this flange is secured the lower edge of a relatively large pulley 5. This pulley is closed at the top by a plate 6, through which extends a central feed hopper 7, having at its lower end an opening 8, which delivers into a central vertical tube or chute 9, carried by a suitable bracket 10, supported by the saddle 4. The chute 9 extends down through the saddle and discharges the material at the center of the annular runway 13, directly over a distributing cone 11. This cone is secured to the concrete base by means of a suitable anchor 12.

The usual screens 15 surround the runway 13, and the pulverized material passes through these screens.

From the upper edge of the wall 2 to the upper part of the inner wall 3 extends a canopy or housing 16, which may be formed of sheet metal, but is here illustrated as made of flexible material, such as canvas. This is tightly held to the upper edge of the wall 2 by means of a hoop 17, which rests in brackets 18 and is secured in position as by pins 19. At its upper edge the canopy 16 is secured to the wall 3 by means of a hoop 20. In order to seal the space around the outside edge of the saddle, I provide an annular hood or shield 21, secured to the upper edge of the wall 3 by means of a hoop 22. The canvas hood extends up over the edge of the wall 3 and thence inwardly and downwardly toward the saddle, where it is secured at its inner edge to another hoop 23. It will be seen that this hoop 23 is not attached to anything, but rests lightly upon the upper surface of the saddle and is capable of "floating," or moving up and down with the saddle.

Surrounding the annular grinding trough or runway 13 is a closed chamber formed partially by the canopy 16 and partially by the concrete base 1. This chamber is divided by partitions 25 into a plurality of hopper-shaped compartments 24, two of such com-

parts being shown. It will be seen that these compartments have sloping or converging walls and bottoms, and at the lowest point of the bottom of each compartment I provide an outlet 26, opening into a pipe 27. The pipes 27 are preferably given a slight pitch and unite to form a main discharge pipe or conduit 28. I provide some suitable means for creating a current of air 10 through the pipes and chambers just described. The means shown in the drawing consists of a centrifugal fan or blower 29, which may be driven by a suitable pulley and belt 30 and 31. The discharge pipe 15 32 from this fan extends down into the pipe 28, as indicated at 33, in Fig. 1, and as will be well understood, the blast of air issuing from the pipe 33 has an injector action which serves to reduce the pressure in the 20 pipes 27 and thus induce air currents therein.

It will be noted that the saddle 4 and associated parts has no fixed shaft or bearings, but is free to move both vertically and laterally within certain limits, as fully described in my said application Serial No. 195,628. The saddle and pulley are driven by means of a power belt 34, engaging the pulley 5, and while in my above mentioned prior application, the saddle was entirely unrestrained, I have observed in practice that with such an arrangement the stress of the driving belt sometimes tends to pull the saddle off center. I have therefore found it desirable to devise some means for overcoming this tendency. As shown in the drawings, I have provided an anchor belt 35 for this purpose. This belt also works over the pulley 5 and passes around a fixed idler 36, journaled in a bracket 37, secured to a post 40 38, or other suitable support. Such anchor belt, while allowing the freedom of movement necessary to successful operation, resists the pull of the driving belt, and prevents undue lateral displacement of the saddle.

In order to keep the screens 15 clean and open, I preferably provide one or more brushes 39. These brushes are secured to the edge of the saddle 4 and revolve therewith. Each brush is supported by means of a shank 40, which is hinged at 41 to a bracket 42, secured to the saddle. A resilient wire spring 43 is bent around the hinge and passes under the shank 40 in such 55 a way as to urge the brush 39 outwardly against the screens 15, as will be apparent.

The operation of my improved dry mill will now be readily understood. The material to be ground is fed in through the hopper 7 and chute 9, whence it is delivered on to the cone 11 and passes therefrom to the annular trough under the balls. It will be seen that all parts of the mill are enclosed practically air-tight, the only opening being at the bottom of the hopper 7. When

therefore the fan 29 is put in operation, a strong current of air will be caused to flow down through the hopper 7 and chute 9 out over the trough 13 and through the screens 15, thus forcing the dry pulverized material to 70 pass through such screens into the compartments 24. From thence the material is carried by the air currents through the pipes 27 and 28 to any desired point.

It will thus be seen that I have provided 75 simple but efficient pneumatic means for carrying away the dry pulverized material from a crushing mill, and it is thought that the many advantages of my invention will be obvious to those skilled in the art. 80

What I claim is:

1. In a crushing mill, the combination with a circular grinding device, of a closed annular chamber surrounding said device and extending below the same, means for feeding material to be ground into the center of the grinding device, and means connected with the bottom of said annular chamber for reducing the air pressure therein so as to cause the dry pulverized material from the grinding device to flow into and through such chamber. 85

2. In a crushing mill, the combination with an annular trough, grinding balls adapted to run in said trough, a saddle overlying said balls, a feed chute at the center of said saddle, a chamber surrounding and extending below the trough and balls, and means for reducing the air pressure in 90 said chamber so as to cause a current of air 100 to flow downwardly through said feed chute and over said annular trough so as to carry the dry pulverized material into said chamber. 95

3. In a crushing mill, the combination with a casing of an annular trough enclosed therein, of balls adapted to run in said trough, a saddle overlying said balls and forming an air-tight partition, an open feed chute extending through said saddle, means 105 for preventing the entrance of air between the casing and the edge of said saddle, a closed chamber surrounding said annular trough and casing, and means for causing a current of air to flow into said feed chute, across said annular trough and into and through said chamber so as to carry away 110 the dry pulverized material. 115

4. In a crushing mill, the combination with an annular trough and balls running therein, of a saddle overlying and rotating with said balls, said saddle having an opening near the center thereof, a closed chamber surrounding said annular trough, means for reducing the pressure in said chamber so 120 as to cause air to flow through the opening in the saddle, over the annular trough and into and through said chamber, and means for preventing the entrance of air around the edge of said saddle, such means com- 125 130

prising an annular flexible hood having at its inner edge a floating hoop adapted to rest on the saddle.

5. In a crushing mill, the combination with a circular grinding device having rotating parts, of screens surrounding said grinding device, means for causing a current of air to flow outwardly through said grinding device and screens, to carry away 10 the dry pulverized material, a brush pivotally carried by a rotating part of the grinding device and arranged to sweep over said screens so as to continually clean the same, and a spring for urging said brush against 15 the screens.

6. In a crushing mill, the combination with an annular trough and balls adapted to roll therein, of means for conveying material to be ground into the center of said 20 trough, a closed chamber surrounding said trough and divided into a plurality of hopper-shaped compartments extending below such trough, each of said compartments having a sloping bottom, a pipe tapping the 25 lowest point of the bottom of each compartment, and means for creating a current of air through said pipes so as to carry away the dry pulverized material from the annular crushing trough.

7. In a ball mill, the combination with an annular trough and balls, of a saddle overlying the balls and free to move laterally thereon, a belt pulley secured to said saddle, a power belt running around said pulley, and means independent of the trough 35 and balls for preventing undue lateral shifting of the pulley and saddle due to the stress of said belt.

8. In a ball mill, the combination with an annular trough and balls, of a saddle 40 overlying the balls and free to move both vertically and laterally relative to the trough, means for rotating said saddle comprising a power wheel carried by the saddle, and restraining means engaging said wheel 45 for preventing undue lateral displacement of the wheel and saddle.

9. In a ball mill, the combination with an annular trough and balls, of a saddle overlying the balls and free to move laterally 50 thereon, a belt pulley secured to said saddle, a power belt running around said pulley, an anchor belt also working over said pulley, and a fixed idler around which said anchor belt passes. 55

In testimony whereof I affix my signature.

OSCAR ANDREW ELLIS.
